UNITED STATES PATENT OFFICE.

EDWARD N. BROWN, OF CLEVELAND, OHIO.

DAVENPORT-BED.

1,144,293.

Specification of Letters Patent. Patented June 22, 1915.

Application filed April 20, 1914. Serial No. 833,282.

To all whom it may concern:

Be it known that I, EDWARD N. BROWN, citizen of the United States, residing at Cleveland, in the county of Cuyahoga and State of Ohio, have invented certain new and useful Improvements in Davenport-Beds, of which the following is a specification.

This invention relates to a davenport-bed, all substantially as shown and described and particularly pointed out in the claims.

In the accompanying drawings, Figure 1 is a plan view of the structure showing the bed open, and Fig. 2 is a front elevation of Fig. 1. Fig. 3 is an enlarged perspective view of one corner of the bed and the davenport seat suspended by links therefrom. Fig. 4 is a cross section of Fig. 1 showing the bed open. Fig. 5 is a sectional elevation on line 5—5, Fig. 6, showing one of the bed connecting links enlarged. Fig. 6 is a cross section of the bed corresponding to Fig. 4 in the line on which it is taken but showing the bed sections in the partially opened position to which the springs therewith raise the said parts when released from the back. Fig. 7 is an end elevation of the back. Fig. 8 is a cross section showing the bed folded. Fig. 9 is an end elevation of the seat and the two bed sections and their connections and of sundry other parts therewith. Fig. 10 is an inside perspective view of one of the end or arm members of the main frame, and Fig. 11 is a plan view on line 11—11, Fig. 9, and showing a portion of the inner frame on which the bed sections are mounted. Fig. 12 is a rear elevation of the structure with the bed folded. Figs. 13, 14 and 15 are views of details by which the top rail or bar is connected with the end members, and Figs. 16 and 17 are side and edge views respectively of the end levers on the back.

Several distinct features of construction and operation characterize the structure as thus shown which are believed to be entirely new and original in the art, and the said features or improvements consist:

First, in the means which fasten or join the top rail 3 with the end members or supports 2 of the main frame without the use of dowels, braces or the like, as heretofore, and thus materially simplify the connection between said parts and the labor of assembling the parts as well as avoiding the expense and labor of boring the said ends and top rail for the dowels. This also avoids the

ever present danger of checking or cracking the ends of the top rail as is always liable when it is bored for dowels and which develop a constant weakness in the frame. 60 These objections are overcome and remedied in the present bed by means of the parts shown enlarged in Figs. 13—14 and 15 and which comprise a bracket b which has flanges with screw holes 4 through the same 65 by which it is firmly secured to the rear and top portion of each end member 2, as seen clearly in Fig. 10. This bracket has a walled tapering seat 5 for a companion wedge-shaped bracket b' fixed on the bottom and 70 end of the top rail 3 and a strong horizontally positioned screw 6 engages through the bracket b' into the threaded boss 7 in bracket b to draw said parts firmly together in a horizontal direction. A screw 8 is headed or fixed in bracket b' and depends therefrom through open slot 9 in seat 5 to be engaged by a nut 10 beneath, and the brackets b and b' are thus firmly locked together vertically and an easily separated connection is 80 effected without marring or endangering the connected parts.

Second. My next improvement consists in the back operating and connecting mechanism which avoids the objections found in 85 former structures of this kind wherein there was more or less adjusting of parts required and certain of the parts were necessarily mounted on the end members of the frame. In my present construction the back itself 90 carries all the said mechanism and there are no adjustments whatever. This mechanism comprises a lever l as the main element, and which has the shape shown in Figs. 16 and 17, and is pivoted near its upper end at 12 95 on an ear or clip 14 secured to the end and rear of the frame carrying the back B which, in turn, hangs or is hinged from the front edge of top rail 3, Fig. 4. The said lever l has its lower end offset inward or laterally as seen at 18, Fig. 17, to bring the hook 20 thereon into position to engage beneath the catch 19 at the corner of the front bed section and to serve as a means of support for said section and the seat S thereon 100 when the bed is folded, Fig. 8. The upper end of said lever has a rearward projection or extension 21 above its pivot 12 to engage the retracting spring 8 therewith and which is fixed to the bottom of back B at its other 110 end. This spring serves to throw said lever normally forward into engaging position

with the said catch or lip 19 on the corner of the front bed section C when the bed is folded, as described. It follows by the foregoing construction that the bed section will 5 automatically engage and rest on said lever when folded and pressed down at the rear and the back will automatically swing forward against the rear edge of the seat, when this occurs, and all trace of the bed will 10 have disappeared. In fact by pressing the bed section c down onto the said levers l the back B is forced forward at its bottom through the action of said levers. The idle position of the lever is seen in Fig. 7, where 15 it is in position to be engaged by lip 19 when the bed is turned down, and from this position the said lever swings into a vertical plane, Fig. 8. As this occurs the back swings over the rear edge of the said bed 20 section relatively as seen in Fig. 8 and causes the wedge 24, fixed on its middle and bottom of the back to ride in over or upon the edge rail 25 of the said section and provide a temporary lock for the back, thus 25 practically holding the said parts in position for use as a sofa or davenport. The said rail 25 has spring enough, Fig. 12, to allow a wedging effect like this to be obtained without injury. In this connection 30 it is also to be noted that the springs S' at the front and bottom are arranged and connected at their ends in such manner as to exert a lifting action on the rear of bed section C from its folded position, Fig. 8, to 35 the inclined position seen in Fig. 6, so that when the back B is pressed rearward to release said section the section will be automatically raised by said springs S' and thus also liberate itself from the levers l.

40 Third. The next material feature of the invention consists in the means by which the folding bed sections are anchored or supported in or by the inner or auxiliary frame within the outer or main frame comprising the ends 2, and the top rear rail or bar 3. The said inner frame is made up chiefly of two front angle iron bars 30 one above and apart from the other as seen in Fig. 8 and angle iron end bars 31 braced in the angles 45 or corners rigidly with or to said longitudinal bars 30 and perfectly rigid therewith. The invention contemplates the easy attachment and detachment of this inner frame from the outer frame, and also the easy and convenient detachment of the bed sections from the said inner frame, and the front board 4 is affixed to this frame. To these ends the end or arm members 2 are provided with right angled rests r, Fig. 10, at their rear 50 and bottom which have slots 34 in their top, and the front of the said side members have rests r' with hooks or spurs 22 at their front adapted to seat the corner posts 32 of the said inner frame thereon, the said 55 posts having open notches of V-shape to en-

gage on said rests and support said frame permanently at the front. The end bars 31 have their extremities fashioned into tongue shape as seen at 33 to enter the slots 34 in the rests r and thus seat the said frame in 70 or upon the main frame. It will be seen that in these supports the inner frame is simply seated and requires no bolts or screws or other troublesome fastenings. The posts 32 extend upward above the upper bar 30 of the inner frame and have the front bed section C pivoted on bolts on the top thereof to swing to open and closed positions, and the rear bed section is connected to the front section by links or yokes 35 which provide the only connection between said sections. The said links are extra heavy and rigid and overlap both ends of said sections at their pivots 36 to make the connection as rigid as possible and preserve 80 the folding effect. This effect is especially important because there are no endwise braces at the middle of the bed to prevent sagging at the middle of the mattress m as in this class of beds generally. The said 90 mattress m is a continuous webbing from front to rear covering both bed sections, and the said links or yokes 32 are the exclusive means to keep the mattress stretched and to prevent sagging. To this end the 95 said links are supplemented and strengthened by the bearings 38, bolted to the respective bed sections at the said pivots 36, and the said bearings are of semi-circular form with a right angled flange through 100 which they are secured to said frames or sections. It follows that when the frames are in partially folded position, Fig. 6, the said links come opposite said bearings and are confined to the same working relation as 105 when the sections are down and the said links lie against the ends thereof. Otherwise or without said extra bearings the tendency would be to pull the links loose on their pivots and cause sagging of the mattress. Obviously, the front of the outer or 110 main frame is connected between its ends by the inner frame engaged therewith on the hooks 22, and the front board 4 has the skirting of the seat attached thereto and 115 which closes the structure at the front and avoids exposure of the interior parts.

In Fig. 8 the connecting link 35 is shown to have such length that when the two bed sections are folded the rear section will be 120 down and out of the way and ample room is made between the two sections to receive the bedding. In this position, also, the semi-circular bearing plates bear against said links and serve as strengthening parts as described. The face of these bearings is flush 125 with the outer surface of the ends of the bed sections.

It should be explained that when the bed section C contacts through its engaging lip 130

19 with the hook 20 of lever 7 and is then further depressed the said lever forces the back forward at its bottom owing to the position and pivot of the lever and the swing 5 of the back from the rail 3 above.

The springs S' are idle until the bed sections approach to about the position seen in Fig. 6. Assuming that the sections are to be folded from this position the said spring 10 will be put under increasing tension as the folding proceeds. Thus, a link 40 connects the spring with the frame D back some distance on its end and a right angled plate 41 fixed on said frame bears edgewise on said 15 link. The link 42, pivoted at one end on cross bar 31 of the inner frame and on the said section D back toward its rear portion, Figs. 4 and 6, forces the said section rearward as it is lowered through links 35, and 20 the joint action of the parts is to put said spring under its extreme tension when the sections are folded. In the raised position of the parts the link 42 serves as a support for the inner bed section. Hence, also, when 25 back B is pushed from over the rear of bed section C the said section comes at once under the lifting tendency of the spring mechanism described and if the spring S' be strong enough it will be raised to about the 30 elevation shown in Fig. 6. Then the farther tilting of the said section to full open position is an easy operation by hand and the rear section is raised as shown in Fig. 4.

When the bed sections are completely unfolded as shown in Figs. 1, 2 and 4, the links 35 are parallel with the end rails and seated on rest portions 37 (see Fig. 2), thereby preventing collapse of the section D at its joint portions, and the support afforded by rests 40 37 and the links 35 also assist in upholding the front section C, although the folding legs 43 are mainly relied upon to support the section C when unfolded. The seat S is suspended from rail 25 of section C by 45 hinged loops or links 44 which are detachably engaged with open clips 45 on the seat (see Fig. 3).

The bracket b has a front extension 11 which affords a rest for the bottom strip 3' 50 which is secured to rail 3 and the weight of the back B is sustained by this extension when the assembling and separating operations of the rail 3 with the ends 2 is being carried on.

55 What I claim is:

1. The bed described having two folding sections and links connecting the ends thereof across the fold line and a wire mattress stretched across said sections, and bearing

plates fixed on said sections in a plane with 60 the ends thereof and extending above said ends in position to brace the said links when the sections are folded.

2. A davenport bed having a swing back and levers pivoted on the ends thereof and 65 a pivotally mounted bed section adapted to make hook connection with said levers.

3. A davenport bed as described, having a swinging back and levers pivoted on the 70 ends thereof provided with springs to throw them forward, and a folding bed section provided with catches at its ends and bottom adapted to engage the lower ends of said levers.

4. The structure described comprising a 75 swinging back and spring controlled levers thereon having hooks at their ends, in combination with a bed section having lips adapted to engage over and rest upon said hooks, and said levers constructed to press 80 said back forward when engagement is made by said bed section with said levers.

5. The structure described comprising a swinging back and a folding bottom adapted 85 to be turned beneath the edge of said back, means temporarily engaging the back with said section and a wedge shaped part on said back adapted to bear on the edge of said section and hold the said parts separably together. 90

6. A main frame for a davenport-bed having slotted plates inside at its rear and bottom and hooks at its front and bottom, in combination with an inner frame having front and end portions rigidly connected 95 and provided with posts seated on said hooks and tongues on said end portions inserted in said slots, and two bed sections supported from the tops of said posts and links connecting the rear of said bed-frames with the 100 ends of said inner frame.

7. In a folding bed as described, a set of bed sections and an inner frame on which said sections are pivotally supported through the front section, rigid links pivoted at their 105 ends on the ends of said sections across the space between them, and raised bearings for said links on said sections adapted to confine the links to working relations when the sections are turned from unfolded to folded 110 position.

In testimony whereof I affix my signature in presence of two witnesses.

EDWARD N. BROWN.
